UNITED STATES PATENT OFFICE.

CLAUD J. CLEFTON, OF OWATONNA, MINNESOTA, ASSIGNEE, BY MESNE ASSIGNMENTS,
TO EUTH P. CLEFTON, OF OWATONNA, MINNESOTA.

BURNER.

Application filed February 8, 1923. Serial No. 617,891.

This invention relates to burners for gas, preferably acetylene, and while it is adapted or designed particularly for use in a flat iron, it may be employed for other purposes 5 where a burner of this design can be used.

The object of my invention is to provide improved means for mixing the gas and air and preventing the objectionable alarming popping sound which frequently follows 10 the shutting off of the gas.

A further object is to provide improved means for connecting the burner with the base of the iron to prevent the accidental withdrawal of the burner from the iron and 15 the danger of fire resulting from such withdrawal by a child or some person unfamiliar with devices of this kind.

The invention consists generally in various constructions and combinations all as hereinafter described and particularly pointed 20 out in the claims.

In the accompanying drawings forming part of this specification:—

Figure 1 is an outside view of a burner 25 embodying my invention;

Figure 2 is a longitudinal sectional view of the same;

Figure 3 is a side view partially in section of a flat iron showing my invention applied 30 thereto;

Figure 4 is a sectional view on the line 4—4 of Figure 2;

Figure 5 is a sectional view on the line 5—5 of Figure 2;

Figure 6 is a sectional view on the line 6—6 of Figure 2;

Figure 7 is a detail view of a portion of the burner.

In the drawing, 2 represents the burner 40 head having a tapered end 3 provided with an orifice 4. The head is in the form of a shell interiorly threaded at one end to receive an exteriorly threaded plug 5 formed on a shank 6 in which a gas passage 7 is provided leading to the interior of the head 2. Air intake ports 8 are provided in the 45 wall of the shank and a gas tip 9 is mounted in the shank and communicates through a tube 10 with a suitable source of gas supply.

A flange 11 is formed at the inner end of 50 the shank 6 and provided with a beveled surface 12, and when the head of the burner is thrust into the socket 13 in the base of the iron 14, the flange will contact with the outer 55 wall of the socket and the beveled surface

of the flange will engage a spring-pressed pin 15, forcing it outwardly against the tension of its spring until the flange has moved past the pin whereupon the pin will spring back to its normal position in the rear of the 60 flange and lock the burner firmly in its socket preventing the withdrawal thereof until the pin is withdrawn by grasping the finger grip 16 thereon.

Within the head 2, is a removable shell 17, 65 open at each end and provided with flanges 18 and 19. A plate 20 is seated against the flange 19 and is imperforate except for a series of holes 21 provided therein near its periphery. A series of rings 22 are placed 70 within the shell 17 and spaced from one another and from the plate 20, each ring having holes therein to register with the holes 21 in the plate 20. At the end of the shell 17, a ring 23 is provided that is imperforate, thereby closing the direct passage 75 through the holes in the other rings, said ring 23 and the perforated rings being held in place by the flange 18 and all of them being spaced apart as described.

The central passage 24 through the rings 80 communicates with the passage 7 and is closed at its inner end by the plate 20 so that gas flowing through the passage 7 can not pass directly through the shell but must flow outwardly at right angles thereto between the perforated rings and into the holes therein, and thence through the holes 21 in the plate 20 to the tapered end of the burner head and the orifice 4. In this way, the gas 85 is compelled to follow a tortuous path and is so broken up and mixed with the air that there is no possibility of backfire or popping in the burner when the gas is shut off.

The gas mixer, it will be noted, has a plurality of narrow radial gaps through which the gas is delivered to the ports leading to the burner tip. The number of these gaps will vary, of course, with the desired capacity of the burner, more rings being used 90 and more gaps provided when it is desired to pass a larger volume of gas to the tip. Whenever desired, the shank member 6 may be removed and then access easily had to the mixer for cleaning or other purposes.

I claim as my invention:—

1. A gas burner comprising a shell having a tip and discharge orifice therein, a sleeve fitting within said shell, a disc arranged within said sleeve and having a closed cen- 110

tral portion and perforations encircling said central portion, a plurality of rings also fitting within said sleeve and spaced apart, and having holes to register with each other and with the holes in said disc, the outer ring of the series having no perforations therein, means having a gas passage communicating with said sleeve and rings, the gas flowing outwardly between said rings and passing through the holes therein to said tip.

2. A gas burner comprising a tip having a discharge orifice, a series of rings fitting within said tip and spaced apart, each ring being provided with a series of perforations adapted to register with the corresponding perforations of the other rings, a ring having no perforations therein at one end of said group, a disc at the opposite end of said group having perforations to register with those in said rings, said disc closing the direct passage through said rings and compelling the gas to flow outwardly between said rings to the perforations therein.

3. A gas burner comprising a shell having a tip and discharge orifice therein, a gas mixer fitting within said shell and having a central passage that is closed at the end adjacent said tip, the walls of said passage having a series of narrow gaps radiating from said passage and said mixer having ports leading to said tip and communicating with said gaps.

4. A gas burner comprising a shell having a tip and discharge orifice therein, a gas mixer fitting within said shell, and comprising a sleeve having a passage open at one

end and closed at the other, the walls of said passage having a series of narrow gaps radiating therefrom, and also having a series of ports communicating with said gaps and leading to said tip.

5. A gas burner comprising a shell having a tip and discharge orifice therein, a gas mixer fitting within said shell and comprising a sleeve, a series of rings fitting within said sleeve and spaced apart to form radiating gaps between them, means for closing the central opening through said rings and sleeve adjacent said tip, and said rings having ports communicating with said tip and with said gaps.

6. In a gas burner, a mixer comprising a sleeve, a disc fitting within said sleeve and having an imperforate central portion and perforated near its periphery, a series of rings fitting within said sleeve and spaced apart to form gaps between them, and having ports for communication with the perforations in said disc and with said gaps, and means within said sleeve for closing the ports in said ring remote from said disc.

7. A burner comprising a shell having a tip and discharge orifice therein, a gas mixer fitting within said shell and provided with a series of radially extending gaps and gas ports communicating with said gaps and with said tip, and a plug fitting within said shell and when removed permitting the removal of said mixer.

In witness whereof, I have hereunto set my hand this 3rd day of February, 1923.

CLAUD J. CLEFTON.
